UNITED STATES PATENT OFFICE.

HENRY M. LAMBERT, OF PORTLAND, OREGON.

DESIGN FOR A CUSHION-TIRE.

57,363.

Specification for Design.

Patented Mar. 15, 1921.

Application filed April 24, 1920. Serial No. 376,416. Term of patent 14 years.

To all whom it may concern:

Be it known that I, HENRY M. LAMBERT, a citizen of the United States, residing at Portland, in the county of Multnomah and State of Oregon, have invented a new, original, and ornamental Design for Cushion-Tires, of which the following is a specification, reference being had to the accompanying drawing, forming a part thereof.

Figure 1 is a side elevation showing my new design.

Fig. 2 is a fragmentary tread view of the same.

What I claim is:—

The ornamental design for a cushion tire substantially as shown.

HENRY M. LAMBERT.
